UNITED STATES PATENT OFFICE.

HORACE L. COLE, OF WILKINSBURG, PENNSYLVANIA, ASSIGNOR TO WESTINGHOUSE ELECTRIC & MANUFACTURING COMPANY, A CORPORATION OF PENNSYLVANIA.

TRANSFORMER WINDINGS.

Application filed August 6, 1923. Serial No. 655,839.

To all whom it may concern:

Be it known that I, HORACE L. COLE, a citizen of the United States, and a resident of Wilkinsburg, in the county of Allegheny and State of Pennsylvania, have invented a new and useful Improvement in Transformer Windings, of which the following is a specification.

My invention relates to transformers and 10 more particularly to an arrangement of windings therefor.

One object of my invention is to provide a transformer in which the several windings are divided in such manner that the 15 leakage reactance therebetween is substantially zero, at definite points.

It is another object of my invention to provide a transformer in which a plurality of series of coils are so placed relatively to 20 each other that the resultant magnetic reactance between the several groups of windings is substantially zero.

It is also an object of my invention to provide a transformer in which a plurality 25 of windings are divided into series of coils so arranged that the total distance from the coils in any one series to the coils in any other series is substantially equal.

In transformers provided with a plurality 30 of series of coils, each of which series is adapted for generating a particular voltage, it has been found that the reactance between the several series of coils is often times sufficient to cause mechanical and electrical breakdowns between the various coils 35 of the transformer with a resulting liability to short-circuiting and the accompanying dangers of explosion and fire. In order to neutralize the reactance between 40 the several series of coils, I propose to make each coil of substantially the same electrical capacity and to so place the several coils comprising the single series at substantially 45 equal distances from the coils of the other series. It is apparent that the resulting reactance between the respective pairs of series of coils is equal and the resultant leakage reactance produced by all the series of coils is substantially zero.

50 In the accompanying drawings,

Figure 1 is a diagrammatic illustration of an arrangement of transformer coils embodying my invention applied to a transformer having three series of windings.

Fig. 2 is a diagrammatic view, similar 55 to Fig. 1, of a modified form of my invention.

Fig. 3 is a diagrammatic view of an arrangement of transformer coils embodying my invention applied to a transformer having 60 four series of windings.

Fig. 4 is a curve illustrating the distribution of magnetomotive force between the two series of coils throughout the length of the transformer. 65

Figs. 5 and 6 are similar curves showing the relations between the different series of coils.

Fig. 7 is a curve illustrating the distributing of the magnetomotive force throughout 70 the transformer when one series of coils is energizing a pair of series of coils.

In the preferred embodiment of my invention, as shown in Figs. 1 and 2, I provide a plurality of series of coils A, B and C. Each of these series is subdivided into three coils which are mounted on any suitable core member 1. A second system of coils (not shown) may also be mounted on the core member 1. Each series of coils 80 represents the several systems of windings which are customarily placed in a transformer structure, whereby the same transformer structure may be adapted to a plurality of voltages. My invention is applicable to transformers having at least three systems of windings. Each of the coils, comprising the several series, are of substantially the same electrical capacity, although either the number of amperes or the 85 number of turns may not be the same as in the adjacent series of coils. While the figures represent the well-known shell type of construction of the core member, the invention is equally applicable to the core type, 90 or any type which employs the interleaved coil construction for the windings. The invention is not limited to single phase transformers, but is equally adapted for multi-phase transformers. 95

The term "reactance," as employed in this application, is understood to refer to the electromagnetic leakage which takes place between the several systems of windings which are active when the transformer is 100 carrying normal load. There is also an electromagnetic leakage within the active coils themselves, but this factor is usually 105

small in comparison with the leakage between the coils and is being neglected in this application for the reason that the invention is directed to the electromagnetic 5 leakage between the coils. Where, for mechanical or electrical reasons, the shape and size of the coils is such as to cause the leakage reactance within the coils themselves to become appreciable, I can alter the distances d_1 , d_2 , etc., slightly to counterbalance this effect, so that the total effective magnetic leakage reactance between any two systems of windings can be made substantially equal to that between any other two systems 10 of windings, or can be made, within reasonable limits, any desired value.

The distance between the faces of any two adjacent coils is d_1 , and the distance between the adjacent face of one coil and the 20 adjacent face of the third coil is represented by the distance d_2 , and the distances between the end coils of adjacent groups comprising a coil from each of the groups A, B and C is represented by o . From this 25 arrangement it follows that the total distance between the several windings of the series A and the series B equals $2d_1+d_2+2o$. Similarly, the distance between the coils in the series B and the series C to A equals 30 $2d_1+d_2+2o$. By reason of the fact that the several coils of each group are of the same or substantially the same ampere-turns, there will be no magnetomotive force and, consequently, no leakage reactance 35 across the distance o .

This feature is diagrammatically shown in Figs. 4, 5 and 6 which are laid out to scale in accordance with the structures shown in Fig. 1. Fig. 4 shows the magnetomotive force which exists between the coils A and B throughout the transformer. Fig. 40 5 shows similar relation between coils A and C and Fig. 6 shows the relation between the coils B and C. Fig. 7 shows the magnetomotive force which exists when the series of coils A is utilized for energizing the series of coils B and C. It is to be observed that in all of these cases, the magnetomotive force at the points corresponding 45 to the spaces o in Fig. 1 is zero. This relation holds true for any combination of the windings.

In view of this relation between the several groups of windings, the distance over 50 which there is effective magnetomotive force between the windings of each series may be written $2d_1+d_2$. The arrangement of the coils in each group, as shown in Fig. 2, follows the same mathematical formula except that their order is varied.

In the arrangement of coils shown in Fig. 3, there are four series of coils A, B, C and D, and each group of coils represent one coil from each of the series A, B, C and D. 55 The distance between the adjacent faces of

any two coils in each group is indicated by d_1 . The distance between the adjacent faces of the first and third coils is indicated by d_2 , and the distance between the adjacent faces of the first and fourth coils is indicated by d_3 . The distance between the several groups of coils is indicated as o .

The distance between any two series of windings over which there is effective magnetomotive force is equal to $3d_1+2d_2+d_3$.

It will thus be seen that in a four-winding transformer embodying my invention, there are six different groups of coils, the total reactance between any two series of windings being substantially the same.

My scheme may be enlarged indefinitely, and the total reactance between any two series of windings will remain the same. The formula for distance between any two series of windings, across which there is effective magnetomotive force, may be written as

$$(n-1)d_1+(n-2)d_2+\dots+2d_{n-2}+d_{n-1}$$

I have, therefore, provided a transformer in which the several coils comprising each major winding are so placed relative to the coils of the other windings as to produce substantially a zero magnetomotive force between any two groups of coils, and, in addition, a transformed in which the reactance between any two series of coils is substantially the same.

I have not overlooked the fact that in the actual design and construction, where taps in the windings for slightly reduced or increased voltages are required, or for other electrical and mechanical reasons there may be a very small magnetomotive force across the spaces o , o , between the groups, which, for practical purposes will be substantially zero in comparison with the other magnetomotive forces involved.

I do not wish to be restricted to the specific circuit connections or arrangement of parts herein set forth, as various modifications thereof may be effected within the spirit and scope of my invention. I desire, therefore, that only such limitations shall be imposed as are indicated in the appended claims.

I claim as my invention:

1. In an electrical device, a core member, three or more series of coils thereon, said series of coils being so placed relative to one another that substantially equal distances, across which there is a magnetomotive force which produces leakage reactance, exist between the coils of any one series and the coils of any other series.

2. In an electrical device, a core member, three or more series of coils thereon, the several coils of each series being so placed relative to the coils of the other series that the total leakage reactance between any two series of coils is substantially equal to the

total leakage reactance between any other two series.

3. In an electrical device, three or more series of coils, the coils of each series being placed between the coils of the other series, whereby the resultant magnetomotive force producing leakage reactance between all of the coils is substantially zero.

4. In an electrical device, a core member, 10 three or more series of coils thereon, the coils of each series being so placed relative to the coils of the other series that the total effective distance across which there is a magnetomotive force which produces leakage reactance, between the coils of any two series correspond to

$$(n-1)d_1 + (n-2)d_2 + (n-3)d_3 + \dots + 3d_{(n-3)} + 2d_{(n-2)} + d_{(n-1)}.$$

20 5. In an electrical device, a core member, three or more series of coils thereon, adapted for energizing one another, the coils of each series being so placed relative to the coils of the other series that the total effective distance, across which there is a magnetomotive force which produces leakage reactance, between the coils of any two series is substantially equal to the total effective distance between the coils of any other two 25 series.

6. In an electrical device, three or more series of coils, each of said coils being of substantially the same electrical capacity, the coils of each of said series being so placed relative to the coils of the other series 35 that the total reactance between each series of windings is substantially equal.

7. In an electrical device, three or more series of coils, each of said coils being of substantially the same electrical capacity, the 40 coils of each of said series being so placed relative to the coils of the other series that the total effective distance, across which there is a magnetomotive force which produces leakage reactance, between one series 45 of coils and another series of coils is substantially equal to the total effective distance between any other two series.

8. In an electrical device, three or more series of coils, each of said coils being of 50 substantially the same electrical capacity, each of said series being so subdivided and placed relative to the coils of the other series that the magnetomotive force or leakage reactance at definite points in said electrical device is substantially zero.

In testimony whereof, I have hereunto subscribed my name this 2nd day of August, 1923.

HORACE L. COLE.

Certificate of Correction.

It is hereby certified that in Letters Patent No. 1,558,841, granted October 27, 1925, upon the application of Horace L. Cole, of Wilkinsburg, Pennsylvania, for an improvement in "Transformer Windings," an error appears in the printed specification requiring correction as follows: Page 3, at the end of claim 4 strike out the equation, and insert the following instead:

$$(n-1)d_1 + (n-2)d_2 + (n-3)d_3 + \dots + 3d_{(n-3)} + 2d_{(n-2)} + d_{(n-1)};$$

and that the said Letters Patent should be read with this correction therein that the same may conform to the record of the case in the Patent Office.

Signed and sealed this 15th day of December, A. D. 1925.

[SEAL.]

WM. A. KINNAN,
Acting Commissioner of Patents.
